UNITED STATES PATENT OFFICE

ALOIS HLAVA, OF PILSEN, CZECHOSLOVAKIA

RIVETING MACHINE

Application filed March 19, 1931, Serial No. 523,741, and in Czechoslovakia June 4, 1930.

The present invention relates to an adjustable head for pin riveting. In my co-pending patent application Ser. No. 421,621 is described a riveting machine wherein an 5 adjustable head comprises two arms at right angles to each other carrying guides for centring pins.

According to the present invention the apparatus is improved by employing only a 10 single centreing pin used when the machine is making either vertical or horizontal rivet seams, or even obliquely disposed rivet seams, and this centreing pin is adjustable by adjusting means, for example an arm rotating 15 about the axis of the die holder, so that the centreing pin can move in a plane at right angles to the axis of the die holder and be adjusted to any point lying in a sector within this plane. By means of this improvement 20 it is made possible to adjust the apparatus to perform riveting operations upon articles in the greatest variety of positions, as is required in complicated riveted constructions where the rivet seams run in a variety of 25 different directions.

One form of the invention is shown in the accompanying drawing, in which

Fig. 1 is a front elevation and

Fig. 2 a side elevation, both representations being diagrammatic.

On the die carrier 1 is mounted to rotate about the axis thereof a plate 2, which, by means of bolts 3, is attached to the head 4 of the riveting machine. This plate 2 has a 35 slot 5 in which engages the head 6 of the fixing bolt 7, by means of which the adjustable head 8 is fixed, this head being rotatable about the axis of the die. The adjustable head is provided with a single arm 9 for the block 10 which carries a single centreing pin 11 and this pin is adjusted in position to suit the distance between the rivets.

The parts 9 and 10 and 5, 7 and 3 form 45 adjusting means for the single centreing pin 11 which allow this centreing pin to be adjusted through a plane at right angles to the axis of the die holder and to be brought to any point in a sector lying in this plane, so that as will be described below a single centreing pin can be used for horizontal, ver-

tical or obliquely disposed riveted seams at any angle.

In riveting horizontal seams the apparatus is used in the position illustrated in the drawing. If vertical seams are to be riveted the bolt 7 is loosened and the adjustable head is turned through 90° and in this position it is fastened again by means of the bolt 7. In riveting obliquely disposed seams the adjustable head is fixed in the horizontal or 55 vertical position according to the direction of the oblique seam and after first loosening the bolts 3 the adjustable head is brought by means of the worm 12 into the plane of the oblique seam and in this position it is fixed 60 by means of the bolts 3. The turning of the adjustable head is effected by the engagement of the worm 12, which is mounted in a bearing 13 rigid with the head 4 of the machine, with a toothed segment provided on 65 the plate 2.

By this construction according to the present invention above described the riveting of 70 seams in any direction is made possible with the use of a single centreing pin, so that a 75 second arm of the adjustable head becomes unnecessary.

I claim:

1. In a riveting machine, the combination 80 of a riveting head carrying a die holder, a support rotatable on the riveting head about the axis of the die holder, a single arm rotatable and adjustable on said support whereby said arm may be oscillated more than 90° about the axis of the die holder and a single 85 centering pin carried by said arm.

2. A riveting machine comprising the combination with the elements claimed in claim 1, of means for rotating the support comprising 90 a worm wheel on the support meshing with a worm on the head of the riveting machine.

3. In a riveting machine, the combination 95 of a riveting head carrying a die holder, an adjustable head comprising a hub rotatable about said die holder and an arm extending radially from said hub, a centering pin adjustable in said arm, a support interposed between the riveting head and adjustable head and rotatable about the die holder, 100
